UNITED STATES PATENT OFFICE.

FREDERICK WILLIAM NEUMAYER, OF BALTIMORE, MARYLAND, ASSIGNOR TO MERTHALER LINOTYPE COMPANY, A CORPORATION OF NEW YORK.

LINE-CASTING MACHINE.

1,072,765.

Specification of Letters Patent. Patented Sept. 9, 1913.

Application filed July 21, 1909. Serial No. 508,766.

To all whom it may concern:

Be it known that I, FREDERICK W. NEUMAYER, of Baltimore, State of Maryland, have invented a new and useful Improvement in Line-Casting Machines, of which the following is a specification.

This invention has reference to line casting machines, wherein circulating matrices are composed temporarily in lines, the lines 10 transferred to the face of a mold, to form type characters on the edge of a slug cast therein, and the line thereafter transferred to a distributing mechanism through which the individual matrices are returned to their 15 proper places in the magazine, as illustrated, for example, in United States Letters Patent No. 436,532.

In one form of these machines it is customary to use matrices each containing at 20 different levels two distinct characters or matrices, the machines being provided with means whereby the matrices passing to the line may be assembled at a high or a low level, in order to bring the upper or the 25 lower characters to the casting position, as demanded; a mechanism for this purpose being shown in Letters Patent of the United States to Rogers No. 615,909. In this mechanism, the assembling elevator, in which the 30 matrices are assembled in line, is provided with a short horizontal blade or slide, which may be projected beneath the incoming matrices at the receiving end of the assembler to arrest the matrices at the upper level, 35 and the assembler is further provided with a second and longer blade forming a continuance of the first, for the purpose of maintaining the elevated matrices as the 40 composition of the line progresses. These two blades are provided with handles or handpieces for adjusting them horizontally, so that either or both of them may be thrown out of action at will. The location of these 45 handles is remote from the keyboard by which the matrices are released, and the relation of the parts and the movement of the handles are such that there is an appreciable and material interruption of the keyboard 50 operation whenever the slides, or either of them, are to be adjusted.

The object of my invention is to avoid this loss of time, and to this end it consists in parts arranged upon or immediately adjacent to the keyboard and connected through 55 intermediate devices with the slides in the

assembling elevator, so that they may be instantly operated by the compositor, by a movement of the hand a slight distance away from the position it occupies when finger- 60

Figure 1 is a perspective view showing the keyboard and the assembling elevator of a Mergenthaler linotype machine with my improvements applied thereto. Figs. 2, 3 and 4 are plan views illustrating the matrix controlling devices and the means for operating them. 65

Referring to the drawings, A represents the keyboard of an ordinary line casting machine, including the fingerkeys designating 70 the different characters and serving to release the corresponding matrices, that they may pass to the line in course of composition; B represents the assembling elevator, so-called, channeled horizontally in its upper 75 end to receive and support the matrices which are delivered successively thereto, in a manner well understood in the art. This assembler is movable vertically in the usual manner, for the purpose of lifting the composed line to the devices by which it is transferred to the casting mechanism. 80

When the parts operate in the normal manner, the matrices are sustained at their lower level, on the stationary shoulders or ledges in the assembler. In order to arrest and maintain them at a higher level, I provide an assembler with the two horizontal blades i^{10} and i^{11} , which correspond, so far as their function is concerned, to the blades 85 indicated by like numbers in Patent No. 615,909.

The blade i^{10} , which extends the greater part of the length of the assembler, is mounted in a horizontal slot therein, and is movable both endwise and edgewise. It may be drawn forward edgewise until its inner edge is flush with the inner wall of the assembler. In this position the blade is inactive, and all the matrices are permitted to remain at the 100 lower level. When, however, the blade is moved edgewise to the rear, its inner edge will project into the assembling channel, in position to rest beneath and sustain at a high level those matrices which are delivered 105 upon it.

The blade i^{11} is located at the receiving end of the assembler, for the purpose of arresting the incoming matrices individually at the upper level, that they may be ad- 110

vanced upon sustaining blade i^{10} . The blade i^{11} is of sector form, and fits against the end of blade i^{10} , which has a corresponding curvature. The blade i^{11} turns on a vertical 5 pivot, i , in the assembler, so that it may be swung forward to the operative position shown in Fig. 2, to arrest the incoming matrices, or swung backward to the position shown in Fig. 3, so that its end can stand 10 beyond the incoming matrices and permit them to pass downward to the lower level.

For the purpose of swinging the blade i^{11} to and from its operative position, an arm, i^3 , is provided, which is pivoted to the large 15 blade i^{10} at i^4 , and its opposite end is provided with a pivoted finger, i^5 , acted upon by a spring, i^6 , which holds it normally in the position shown.

The swinging finger i^{11} is provided with 20 a stud, i^7 , which projects downward between the finger i^5 and spring i^6 , so that as the arm is vibrated, it swings the finger i^{11} to and from its operative position. The stud on the finger could extend into a slot in the 25 arm i^3 , but the pivoted finger and spring serve as a yielding connection to relieve the finger i^{11} from strain in the event of its encountering resistance from a matrix when its actuating devices are moved.

30 The slide i^{10} is provided with two offset or angular slots, i^8 , which receive the upper end of rigid studs, i^9 , so that when the slide is moved endwise to the left, the slots and studs will cause it to move edgewise to the 35 front; or, in other words, to the inoperative position, as shown in Fig. 4. When, on the contrary, the slide is moved endwise to the right, the slots and studs cause it to move edgewise into the assembler, to the positions 40 shown in Figs. 2 and 3, that it may sustain the matrices arrested at the upper level by the blade i^{11} . The blade i^{11} is provided with an upright lip i^{12} , which acts to hold the last matrix from falling off the end of the blade 45 when the latter is withdrawn from its active position to allow the succeeding matrix to pass down to the lower level.

I will now describe the means whereby 50 the operator is enabled to adjust the two blades i^{10} and i^{11} while his hands are adjacent to the operative positions on the keyboard.

The slide actuating arm i^3 is engaged by 55 the upper end of a rod, a , having universal motion. This rod is connected at a^1 by a horizontal pivot to a rock shaft, a^2 , seated in the assembler frame. By moving the lower end of the rod a to the right and left, and forward and backward, it may be caused 60 to operate the arm i^3 in such manner that it will throw either or both of the blades i^{10} and i^{11} into or out of action. The lower end of the rod a is cupped and adapted to fit upon and receive motion from a rod, b , 65 which is extended downward through a fixed

supporting plate, c , and provided with an enlargement, b^1 , resting on this plate, so that the rod may rock freely in all directions. A spiral spring, d , encircles the rod and bears at its upper end against a collar thereon, for the purpose of urging it upward and keeping it in engagement with the arm a . 70

By reason of the character of the connection between the rods a and b , the former will separate from the latter when the elevator rises to deliver the assembled line, and the connection of these parts will be automatically reestablished on the descent of the elevator, the cupped end of rod a seating over the ball on the rod b as the elevator reaches its receiving position. 75

The rod b has its lower end, below its supporting plate c , extended through the rear end of an arm, e , which is extended 80 forward along the side of the keyboard, A . This arm e is provided at the forward end with a handle, e^1 , by which it may be moved forward and backward. The arm e has dependent arms, e^2 , mounted to slide and rock 85 on a fixed shaft, e^3 . The arm e is also provided on the upper edge with a stud, e^4 , arranged to traverse an angular slot, e^5 , in the supporting frame. A spring, e^6 , secured to the frame, bears on the stud e^4 , and tends 90 to hold the parts in any position in which they may be left.

As the arm e is moved endwise forward and backward, it vibrates the rod b , which in turn vibrates the rod a , so that the upper 100 end of the latter will swing the arm i^3 inward and outward, causing it in turn to swing the blade i^{11} to and from its operative position. When the blade i^{11} is set in the position shown in Fig. 2. When the arm e is moved forward, the blade i^{11} is swung backward to the inoperative position shown in Fig. 3, 105 permitting the matrices to pass to the lower level. 110

The rocking motion of the arm e to the right and left of the shaft e^3 swings the lower end of the rod b to the right and left, causing its upper end to move in the reverse directions. The upper end of b actuates the 115 rod a , causing its upper end to slide the arm i^3 horizontally to the right or left, the arm in turn carrying with it, through the hinged connection i^4 , the blade i^{10} , which is moved endwise and at the same time caused to 120 move forward and backward edgewise.

When the plate e is rocked to the left, the blade i^{10} is thrown forward out of its operative position, as shown in Fig. 4, and when the part e is moved in the reverse direction, the blade i^{10} is moved inward to the operative position, as shown in Fig. 2. 125

The rocking movement of the blade is caused by the movement of the stud e^4 , traversing the sinuous grooves e^5 . When it 130

is required to operate only the finger i^{11} , the arm is drawn forward only a portion of the distance possible, so that the stud e^4 will remain in the straight portion of the slot in which it normally stands, as shown in Fig. 1. If, however, the arm e is drawn still further forward, the stud e^4 will pass into the deflected or angular portion of the slot e^5 , and the effect will be to rock the arm e laterally.

From the foregoing it will be seen that all the vibrating blades may be moved instantly either from or to their operative positions by simply moving the slide e endwise a greater or a less distance.

Having thus described my invention, what I claim and desire to secure by Letters Patent is:

1. In combination, the assembler, the swinging blade i^{11} , the sliding blade i^{10} , and a common operating means for the two blades.

2. In combination, the assembler, the matrix arresting blade, the matrix sustaining blade, a common device for adjusting the two blades, the sliding and rocking plate e , and connections from said plate to the blade adjusting device.

3. In combination, the assembler to receive matrices, a blade, i^{10} , to sustain matrices above the normal level and provided with a curved end, and a sector-shaped, pivoted plate to arrest the matrices at said upper level, said pivoted blade fitting in the curved end of the blade i^{10} .

4. In combination, the assembler, the matrix sustaining blade i^{10} , and the pivoted blade i^{11} having the lip i^{12} to engage and hold the matrices and pivotally movable about a center in the plane of the blade i^{10} .

5. In combination, the assembler, the matrix sustaining blade i^{10} formed with angularly inclined slots, and the pins passing through said slots, with means to move

the blade endwise, whereby it is simultaneously compelled to move edgewise.

6. In combination with the blades i^{10} and i^{11} , and means connecting them, the operating rods a and b , and plate e , for moving the latter.

7. In combination, the blade i^{10} , guided longitudinally and laterally, the pivoted blade i^{11} , the connecting arm i^8 , and means for moving the latter endwise and sidewise.

8. In a line casting machine, in combination, the movable assembler, the matrix arresting blade, the matrix sustaining blade, and means to adjust both of said blades, said means being located on a support independent of the movable assembler.

9. In a line casting machine, the vertically movable assembler and movable means therein to control the height of the matrices, in combination with mechanism to adjust the said movable means at will, the said mechanism being located partly on the assembler and partly on the main frame and arranged to connect and disconnect as the assembler is raised or lowered.

10. In combination, the assembler, the matrix arresting blade, the matrix sustaining blade, and common operating means whereby they may be simultaneously adjusted to operative or inoperative position.

11. In combination, the assembler, the matrix arresting blade, the matrix sustaining blade, and common operating means for both blades, whereby they may be simultaneously adjusted, or the arresting blade alone adjusted, at will.

In testimony whereof I hereunto set my hand this nineteenth day of June, 1909, in the presence of two attesting witnesses.

FREDERICK WILLIAM NEUMAYER.
